United States Patent Office.

JOHN MCADAMS, OF BROOKLYN, NEW YORK.

Letters Patent No. 99,453, dated February 1, 1870.

IMPROVEMENT IN HINGES FOR SHOW-CASES.

The Schedule referred to in these Letters Patent and making part of the same.

To all whom it may concern:

Be it known that I, JOHN MCADAMS, of Brooklyn, in the county of Kings, and State of New York, have invented a new and useful Improvement in Hinges for Show-Cases, of which the following is a full, clear, and exact description, reference being had to the accompanying drawing, forming part of this specification, and in which—

Figure 1 represents a longitudinal view of my improved spring-hinge, when open;

Figure 2, a similar view of the same, when closed; and

Figure 3, a longitudinal sectional view of said hinge.

Similar letters of reference indicate corresponding parts.

While my improved hinge is applicable to various purposes, it is more particularly designed for use on show-cases, as applied to those doors thereof which are hinged by their lower edge to the lower part of the rear side of the case; and in such connection, it is preferred to associate my invention in this description, by way of showing the convenience and superiority of said hinge; and

The invention consists in combining with the buts, joint-pin, and spring, a divided sleeve, inclosing said spring, whereby it is protected from injury, or becoming clogged with dust, which would in time impair its operation, and at the same time, a neater finish is given to the whole device.

Referring to the accompanying drawing—

A A' are but-hinges, of ordinary construction, but connected by a centre or joint-pin, B, common to both, and arranged at a suitable distance apart, according to the length of the door, edge, or surface they are designed to be applied to.

Coiled around the rod B, between the buts A A', is a spiral spring, C, having its ends hooked or bent, to connect with the buts through holes *a a* therein, the

one end of said spring connecting with the stationary leaf of the one but, and the other end thereof with the movable leaf of the other but. This forms a spring-hinge, made up of combined buts, having not only a joint-pin common to both, but spring also, and the latter attached to the buts direct, without impairing their strength at the knuckle, or otherwise, and wholly disconnected, so far as positive attachment is concerned, from the rod. Such hinge, as a whole, is ready at once to be applied, as required, without any separate fitting of the spring or its parts, by simply screwing the buts to their places.

D D' are sleeves, arranged between the hinges or buts A A', and fitting the one into the other, subject to a collar-lock or stop, as at *b*, the ends of the spring C passing through holes in the outer ends of the sleeves, so that the latter are free to turn independently of each other in the coiling or uncoiling of the spring. These sleeves serve to protect the spring C from injury and dust; also, to force the buts to the distance apart they assume under a wound-up condition of the spring, thereby simplifying the fitting of the combined hinge to its place.

A spring-hinge, thus constructed, meets all the requirements hereinbefore specified for such a device, as applicable to show-cases, and constitutes a marketable entirety or commodity that will be found very convenient, and of no small public utility.

What is here claimed, and desired to be secured by Letters Patent, is—

The combination of the sleeves D D' with the buts A A', the spring C, and the centre or joint-pin B, all constructed and arranged substantially as shown and described.

JOHN MCADAMS.
